BLOWPIPE MACHINE

Arthur M. Keller, Livingston, N. J., assignor to
The Linde Air Products Company, a corpora-
tion of Ohio

Application May 30, 1944, Serial No. 538,015

22 Claims. (Cl. 266—23)

1

This invention relates to blowpipe machines, and more particularly to machines for moving one or more cutting blowpipes transversely of a workpiece or elongated ferrous metal stock to cut the stock into shorter lengths.

In a steel rolling mill, the rolling operation produces elongated bars, billets, or slabs, which may be round, rectangular, or other shape in cross section. Blowpipe machines heretofore have been limited to operate upon only one shape of bar or slab, or have required elaborate adjustment to convert the machine for operation upon another shape. It is therefore a principal object of the present invention to provide a blowpipe machine which will operate substantially equally well on round, rectangular, or other shaped stock, with little or no adjustment for the transition from one shape to the other.

One type of prior blowpipe machine comprises a boom adapted to be extended over the stock from a position clear of the stock, and mechanism on the boom for advancing the blowpipe across the stock during the cut. Other objects of the present invention are to provide, in a blowpipe machine of the boom type, improved means for locating the boom over the workpiece, for traversing the blowpipe across the stock, and for retracting the boom and the blowpipe.

The cutting operation performed by a machine of this type is desirable for trimming the ends of metal stock, or for cutting the same into lengths; and to increase the speed and adaptability of production, further objects of the invention are to provide a machine which can make a plurality of simultaneous cuts, such as trimming both ends, or making intermediate length-severing cuts, and which can be adjusted to vary the spacing between such simultaneous cuts. These objects are preferably accomplished by providing a plurality of blowpipe mechanisms supported on the same boom and laterally adjustable with respect to each other, and common means for actuating these mechanisms.

It is desirable when cutting stock of square or rectangular cross section to start the cut with the blowpipe held at a trailing angle and to complete the cut with the blowpipe held at a leading angle. It is also desirable to retract or raise the blowpipe and its associated mechanism clear of the stock at the completion of the cut, regardless of the cross-sectional shape of the stock. Accordingly, further objects of this invention are to provide a blowpipe machine having improved mechanism for these purposes, and to provide common means for actuating a plurality of laterally

spaced blowpipes simultaneously for these purposes.

Other objects and features of novelty will be apparent as the following description proceeds, with reference to the accompanying drawings, in which:

Fig. 1 is a side elevation of a machine according to the preferred embodiment of the present invention, showing the parts in retracted position in full lines, and in dotted lines in projected position in operative relation to the work;

Fig. 2 is a top plan view of the machine shown in Fig. 1;

Fig. 3 is an elevation of the lower portion of the side of the machine opposite from that shown in Fig. 1, with the cover removed to show details of control mechanism mounted on the base of the machine;

Fig. 4 is a rear elevation of the machine, cover boxes being removed to show the internal construction;

Fig. 5 is a partial front elevation of the machine, showing the blowpipe supporting mechanism;

Fig. 6 is a rear elevation of the blowpipe supporting mechanism shown in Fig. 5;

Fig. 7 is an enlarged vertical cross section taken on the line 7—7 of Fig. 2 through the blowpipe supporting mechanism and showing the trailing arm;

Figs. 8, 9 and 10 are enlarged sections showing various details of the machine. Fig. 8 is taken along the line 8—8 of Fig. 2; Fig. 9 is taken along the line 9—9 of Fig. 6; and Fig. 10, is taken along the line 10—10 of Fig. 9;

Fig. 11 is a longitudinal section through the feed beam, showing the cams for tilting the blowpipe mechanism;

Fig. 12 is a plan of the mechanism for shifting the cams shown in Fig. 11; and

Fig. 13 is a section taken along line 13—13 of Fig. 12.

In the drawings the workpiece or elongated metal stock is represented by a steel billet A, of round, rectangular or other cross section, which may be supported by and propelled into position by a conveyor which is represented by a series of driven rollers R, or the stock may be propelled along such rollers into cutting position.

In general the blowpipe machine comprises a base K, which may be a baseplate forming part of a wheeled truck movable on rails into position adjacent the stock A on the conveyor represented by the rollers R. On the base K, a pair of links L are pivotally mounted, the upper ends of which piv-

totally support a main boom T in position disposed transversely to the conveyor table.

Longitudinally slidably within and extending through the front end of the main boom T is a horizontally movable carriage or feed beam D, the forward end of which carries mechanism for supporting blowpipes B. Under the boom and pivotally attached at one end to the bedplate is a fluid pressure piston P for causing a swinging movement of the main boom T while maintaining it horizontal at all times. Thus the main boom T is moved from the retracted position shown in full lines in Fig. 1, to the parallel position shown in dotted lines. The main boom T is swung forward and down upon the stock A until stopped by the same, to bring the blowpipe B into position for operating upon the billet A or other stock on the rollers R. The piston P is also operable for the reverse movement, to swing the main boom T upwards and backwards to return it to retracted position after the completion of each cut.

For advancing and returning the blowpipe B across the metal stock to be cut, the carriage or feed beam D is propelled in a forward direction and retracted by means of a rack W driven by gearing G from a motor M. This motor may be energized for example by a motor generator set, and by suitable electric controls such as a rheostat, the motor speed can be varied through a wide range of appropriate oxy-acetylene cutting speeds.

The feed beam D at its front end carries a support S which is parallel to the longitudinal axis of the stock to be cut, and on which one or more blowpipe units U are transversely adjustably mounted. In the form shown, the central unit is permanently installed at the center of the machine, and the other two are adjustable for length of stock between cuts. Each unit comprises a frame F on which is pivoted a blowpipe supporting and nozzle-projecting trailing arm J, the end of which extends rearward from such pivotal connection. The rear end portion of the arm J is forked to receive a blowpipe B.

The contour of the underside of the trailing arm J is such that it may be trailed or dragged so as to slide across the top surfaces of various shapes of workpieces as the cut progresses, and will maintain proper blowpipe relationship with the surfaces of these shapes. The trailing arm J at all times prevents mechanical contact between the stock and the nozzle of the blowpipe, and being free to oscillate through a limited movement, in so doing proportionately raises and lowers the blowpipe B to maintain the correct relation between the gas discharge orifices of the nozzle of the blowpipe and the surface of the stock A. This trailing arm J is so constructed that in the cutting of round or square bars or slabs within the capacity of the machine, the change-over from one shape to the other is very simple, and does not necessitate any adjustment of the mechanism of the machine, in most cases entailing only cutting speed and oxygen pressure adjustments.

At the completion of the cut, the blowpipes B are simultaneously raised, all gases are valved off, the large pressure fluid cylinder P raises and pushes back the main boom T, and the feed beam drive motor M reverses at its maximum speed, automatically stopping when the feed beam reaches its fully retracted position, the machine then being ready for the next cutting cycle.

In the preferred example of the machine shown, the base K comprises a bedplate 10 mounted on the mill floor and having upstanding supports 11

12 through which extend link-supporting shafts 12, on the outer ends of which are journaled bearings 13 carried by the lower ends of the links L. The upper ends of the links L carry bearings 14 journaled on the ends of shaft 15 in the main boom T.

The links L serve to support the main boom T for parallel motion with respect to the bedplate K, because the shafts 15 on the main boom are spaced apart the same distance as the spacing of the shafts 12 on the bedplate, and the links L are of equal effective length, although differently shaped if desired for clearance purposes, and suitably reinforced or transversely framed to prevent side sway.

The fluid pressure cylinder P has a head bracket 16 pivotally mounted on the bedplate link-supporting shaft 12 between the bearings for the front link. A piston rod 17 for the cylinder P is pivotally connected by a wrist pin 18 to brackets 19 mounted on the rear link L. Fluid under pressure, preferably compressed air, is supplied to the cylinder P by piping shown in Fig. 3, controlled by a valve 20 operated by a solenoid 21. The compressed air system is also controlled by a valve 22 which is actuated by an arm 23 movable with the rear link about its shaft 12.

As shown in Figs. 1 and 3, the rear bracket 11 has an upwardly extending post 25 provided with a socket 26 to receive a portion of the rear link L, the link and socket having registering apertures to receive a locking pin 27, to retain the boom in retracted position when not in use, and avoid gravity projection thereof when the fluid pressure supply is cut off from the cylinder P in taking the machine out of operation.

The main boom T comprises a hollow elongated box-like structure shown in Fig. 4, formed of a floor plate 30, side plates 31 and 32, and a top plate 33. The side plates have bosses 35 for supporting the boom supporting shaft 15. As shown in Fig. 1, the front end of the main boom T has bolted thereto a stop bracket 36 for engaging the top of the workpiece or stock A when the main boom T is in operative position.

As best shown in Fig. 4, the carriage or feed beam D comprises a trough-like structure, having a bottom wall 40 and side walls 41 and 42. The feed beam D is guided for movement lengthwise of the main boom T, by vertical thrust guide rollers 45 journaled on the side plates above and below the bottom wall 40 and extending inwardly to receive therebetween lateral extensions of the bottom wall to retain the same in a horizontal plane. To prevent lateral displacement of the feed beam D, side thrust guide rollers 46 are journaled on the top plate 33 and depend therefrom to engage the outer surfaces of the side walls 41 and 42.

The rack W for driving the feed beam D back and forth within the main boom T, is secured to the underside of the feed beam floor, 40, and meshes with a pinion 47 on a shaft 48 journaled in a pillow block bearing 49 mounted on the main boom floor plate 30 and passing through a flange type bearing 50 in the main boom side plate 31. The shaft 48 has keyed thereto a driving flange 52, connected by a shear pin 53 to a sprocket 54 loosely mounted on the outer end of the shaft 48. The sprocket 54 is driven by a chain 55 from a drive sprocket 56, an idler sprocket 57 being provided to keep the chain taut. The sprocket 56 is driven by the motor M through reduction gear ing V.

For electrical control of the feed beam driving

mechanism driven by the drive motor M, limit switches 58 and 59 as shown in Fig. 2 are mounted on the main boom T and are actuated by suitable cams (not shown) which are carried by the feed beam D. The limit switch 58 is actuated only by overtravel of the feed beam in the forward direction, but the limit switch 59 is actuated by the feed beam D reaching its fully retracted position at the end of its movement in the opposite or rearward direction. The limit switch 59 may be provided with spare contacts for the connection of electrical interlocks to prevent the running of the conveyor table R when the machine is not in its retracted position. As a further safety measure a mechanical stop is provided as shown in Fig. 1, which comprises a bracket 60 mounted on the main boom plate 30 and engaging angle brackets 61 and 62 attached to the underside of the feed beam floor as shown in Fig. 4.

The mechanism for supporting the blowpipes is mounted at the front end of the feed beam D, as shown in Fig. 7. The feed beam D terminates at its forward end in a vertical plate 65 which is rigidly secured to the side walls 42 and the bottom wall 40 and preferably integral therewith. The frame F of the central blowpipe unit U is channel shaped in side elevation, the legs of the channel being bolted to the plate 65 and provided with upper and lower guideways 66 which adjustably receive the laterally extending support S shown in the form of an I-beam 67.

Each blowpipe unit frame F has a plurality of vertical external stiffening flanges 68 which are provided with spaced depending bearings 69 (Fig. 5) in which is journaled a shaft 70. The front end of each trailing arm J is provided with bosses 72 mounted on the outer ends of the shaft 70. The rear end of each trailing arm J is forked to provide a pair of laterally spaced lugs 73 which are pivotally connected to the yoke or fork of the blowpipe holder 74, shown in Fig. 6. The pivotal connection is shown in Figs. 9 and 10, in which the lug 73 carries a screw 75 having a pointed end, engaging a groove 76 in a pin 77 mounted in a boss on the blowpipe holder yoke 74.

The lower surfaces of the trailing arm J and its lugs 73 are hard surfaced with a wear-resistant material such as a tungsten-cobalt-chromium alloy, or other material which is highly resistant to heat, wear and abrasion. These surfaces comprise three portions which engage the stock at different times during the operation. A curved approach cam surface 78 is adapted to engage the stock ahead of the blowpipe during the starting or initial part of the cutting stroke. This is followed by a downward projection or skid 79, substantially aligned with the nozzle of the blowpipe B and adapted to engage and ride upon the surface of the stock during the main part of the cutting stroke. Finally, an upwardly and rearwardly curved receding portion 80 is adapted to engage the stock during the final stage of the forward stroke or cutting operation.

The yoke 74 is formed at the lower end of a tubular holder 81 which provides a mounting for the blowpipe B. The blowpipe may be of any desired construction, the one shown being a conventional tubular jacketed water-cooled type oxyacetylene cutting blowpipe. The tubular holder preferably provides a floating mounting, in which the height of the blowpipe B is determined by a sleeve 82 adjustably clamped on the blowpipe and engaging the top of the holder.

The sleeve 82 is preferably set in position by the operator using a gauge while the blowpipe is on the bench before being inserted in the tubular holder 81.

5 The yoke 74 also preferably serves to support structure for providing auxiliary preheating flames if desired, for example to permit flying starts on hot steel, the preheat structure as well as the cutting blowpipe being gauged and protected by the lugs 73. A collar 84 is adjustably mounted on the blowpipe B by means of a cap screw 85 projecting through a slotted hole 86 in the yoke 74. The collar 84 supports laterally extending curved gas conduits 87 terminating in preheating blowpipe tips 88 arranged to direct preheating gas jets downwardly and inwardly against the work ahead of the jets discharged by the cutting nozzle N of the blowpipe B, as shown in Fig. 6. The conduits 87 are connected by a pipe 90 to a preheat gas mixer 91 mounted on the blowpipe holder 81.

For raising the trailing arm J and the blowpipe mechanism carried thereby to elevated or retracted position, the trailing arm J is formed with an integral crank 92 extending upwardly from the central boss 72 at the front end of the trailing arm J, so as to be pivoted therewith about the shaft 70. As shown in Fig. 5, the upper end of the crank 92 moves in a slot 93 between the pair of stiffening flanges 68, and carries a roller 94 which is engaged by a cam surface 95 carried by a rocker 96 on a shaft 97 journaled in bearings 98 mounted on the lower flange of the I-beam 67. An adjustable stop 99 on the frame F engages the cam surface 95 upon forward movement of the rocker 96 and thereby limits the upward movement of the trailing arm J.

To operate this blowpipe elevating mechanism, the rear side of the rocker 96 is provided with a roller 100, in turn engaged by a pusher rod 102 slidably mounted in a bushing 103 provided in the plate 65. The head of the pusher rod passes through a suitable aperture in the I-beam 67, and the pusher rod extends rearwardly therefrom through the bushing 103 and a slide bearing 104 to the rear of the feed beam as shown in Fig. 12, where it passes through another slide bearing 105 and is connected to the piston of a fluid pressure cylinder 106 mounted on the feed beam floor 40.

For tilting the blowpipe during the cutting stroke to start the cut at a trailing angle and for completing the cut at a leading angle, the upper end of the blowpipe holder 81 has secured thereto a forked blowpipe tilting bracket 107. The limbs of this bracket are spaced apart and both are notched to receive a blowpipe tilting rod 108 secured in the notches by covers 109 which, as shown in Fig. 2, are spaced apart to give lateral support to the rod 108. Between the limbs of the bracket 107, the rod 108 is engaged by a hook 110 which is notched similarly to the limbs of the bracket 107, the notches serving as automatic take-up for wear. The hook 110 is in turn connected to the forward end of a pull rod 112 which extends rearwardly along the feed beam in freely movable relation.

As shown in Fig. 12, the pull rod 112 terminates in a clevis 113 connected to a crank 114 pinned on a shaft 115 journaled in bearings 116 mounted on the feed beam floor 40. A parallel crank 117 pinned on the shaft 115 is connected to a power spring 118. Splined on the shaft 115 is a sliding collar 120 having an upstanding arm 121 carrying a roller 122 adapted to selectively engage

cams 123, 124, 125 and 126 secured to the under side of the top plate 33 of the main boom. The cam which will be engaged by the roller 122 is determined by the position of the splined collar 120, which is shifted by a lever 127 engaging a groove 128 in the collar, and mounted on a pivot 129 on the feed beam floor 40. The collar 120 is held in selected position by a spring pressed ball 130 engaging selected notches or drill points 131 in the shaft.

The central blowpipe unit U which has been described as shown in Fig. 7, is aligned with the main boom T and is rigidly secured to the front end 65 of the feed beam D. When only the central unit is employed, the I-beam 67 may be short, preferably flush with the frame F. But when additional units are employed to make simultaneous cuts at spaced positions along the stock as shown in Figs. 5 and 6, these units are laterally displaced from the central unit, and the I-beam 67 is extended an appropriate distance on one or both sides of the central unit to support such additional units. In these additional units the frame F is closed by a backing plate 131 instead of the plate 65 for the central unit.

To adjust the additional blowpipe units with respect to the center unit for the purpose of determining the length of stock between cuts, a rack 132 is secured under the upper flange of the I-beam 67, and meshes with a pinion 133 on a shaft 134 journaled in a boss on the plate 131 and operated by a handle 135. When this adjustment has been made, the blowpipe unit is locked in position as shown in Fig. 8, by means of a wedge 136 fitting in a socket 137 in the backing plate 131 and engaging the upper flange of the I-beam 67. To facilitate the setting of the additional units, as shown in Fig. 6, a scale 138 may be provided on the I-beam 67 cooperating with a pointer 139 on the unit, for example on the plate 131.

The additional blowpipe units are adapted for the retraction or raising of the blowpipes thereof simultaneously with the central unit, by extending the cam surface 95 on the rocker arm 96 laterally so that it engages the trailing arm crank roller 92 of these additional units. These additional units are adapted for tilting of their blowpipes simultaneously with the central unit, by extending the rod 108 laterally to engage slotted members 140 secured to the respective blowpipe holders 81 of the additional units. The elongated slots of the members 140 permit the trailing arms J of the additional units to ride over cocked billets.

By valving off the center unit and using only the two outboard units, the maximum length between cuts may be obtained for one machine, or two or more machines will allow four or more simultaneous cuts to be made. Obviously an infinite number of variations are possible using combinations of a plurality of units and a plurality of machines.

In setting up the machine for operation, it will be assumed that the base K has been properly positioned with respect to the conveyor table R and that the stock A to be cut has been properly positioned thereon. The pin 27 is removed from the socket 26 to release the link L, and the gas pressures are adjusted for the cutting operation on the particular shape of stock A on the conveyor table R. It is also assumed that the trailing arm J is in the elevated position and that the variable speed of the motor M is adjusted

to drive the feed beam at the cutting speed to suit the material to be cut.

When round stock is to be cut, the provisions for tilting the blowpipe may not be necessary, and if desired the hook 110 may be disconnected from the rod 108 and rest idly on the feed beam floor 40, although the machine will function perfectly with the tilting provision in use. But when stock of polygonal cross section is to be cut, the hook 110 is positioned in engagement with the rod 108, and the lever 127 is operated to shift the roller arm collar 120 to select the cam 123, 124, 125 or 126 suitable for the particular size of stock.

In operation, the large fluid pressure cylinder P is actuated, causing the piston rod 17 to retract and the levers L cause the main boom T and all parts thereon to swing forward and downward until stopped by the stop bracket 36 of the main boom T engaging the top of the stock A. Preferably the cylinder P is actuated by the operator depressing a push button which energizes the solenoid 21 to operate the valves 20 and consequently admits compressed air to the cylinder P.

After the stop bracket 36 is brought to rest on the top of the stock, the cylinder 106 is actuated to release the pusher rod 102, which permits the rock shaft 86 to swing rearwardly, carrying the cam surface 95 with it. This permits the roller 94 to the trailing arm crank 92 to move rearwardly and permit the trailing arm J to descend and contact the surface of the stock.

The drive motor M is then started, preferably by the operator depressing another push button which simultaneously starts the drive motor in the forward direction and by means of suitable electrically operated valves turns on all preheat and cutting gases. The motor M through reduction gearing V drives the sprocket 56 which by means of the chain 55 drives the sprocket 54. Through the shear pin 53 the sprocket 54 drives the flange 52 and its shaft 48 and the pinion 47 thereon, which meshing with the rack W drives the feed beam D forward, guided by the rollers 45 and 46 within the main boom T.

Upon forward movement of the carriage or feed beam D when polygonal stock is being cut, during the initial portion of the cutting stroke the forward portion 78 which is curved downwardly and rearwardly first engages the upper and nearer corner of the stock, and as the trailing arm J moves forward, the surface 78 rides along this corner until the skid portion 79 passes over the corner onto the main portion of the surface of the stock. At the beginning of this stroke, the power spring 118 holds the rod 102 forward so that the transverse rod 108 holds the blowpipes B rearwardly inclined. Thus the cut is started with the blowpipe positioned in the trailing angle shown in Fig. 7.

During the main portion of the cutting stroke, the skid 79 rides over the major portion of the surface of the stock. Meantime the roller 122 having engaged one of the cams 123, 124, 125 or 126, pushes the arm 121 rearwardly against the action of the power spring 118, and pulls the rod 112 rearwardly, which through hook 110, rod 108 and bracket 107, gradually tilts the blowpipe B about the pivot 17, during this intermediate part of the forward movement of the feed beam D.

After the intermediate or major portion of the cutting stroke, the skid 79 rides down off the upper farther corner of the stock, whereupon

during the final portion of the cutting stroke, the skid 79 descends and the upwardly curved rear portion 80 rides down this far corner of the stock. By this time the cam 123, 124, 125 or 126 has completed its action so that the blowpipe has now reached the leading angle, and this leading angle is maintained until the cutting oxygen jet has passed through the final triangular portion of the stock and has completed the cut.

After the cut is completed, the operator presses a push button which stops the motor M. However, if the operator should fail or unduly delay to press the button, and over-travel of the feed beam takes place, the limit switch 59 is tripped by the cam carried by the feed beam, and stops the motor M when the feed beam reaches its fully extended position. At the same time upon completion of the cutting stroke, fluid under pressure, preferably compressed air, is admitted to the cylinder 106, which pushes on the rod 102 in engagement with the roller 100 and rocks the shaft 97, causing the cam surface 95 engaging the roller 94 to tilt the crank 92, thus raising the trailing arm J and the blowpipe and preheat tips carried thereby, clear of the stock for the return movement. Preferably a single push button is provided, which in addition to actuating the cylinder 106, also causes the shutting off of all gases, stops and reverses the drive motor M at a predetermined speed higher than the cutting speed, and reverses the direction of flow of air to the large operating cylinder P. When the feed beam reaches its fully retracted position, the limit switch 59 stops the motor M.

This invention is not to be limited to the precise details disclosed, but instead the invention is to be construed to embrace such embodiments of the broad ideas as fall within the scope of the appended claims.

What is claimed is:

1. Blowpipe apparatus comprising, in combination, a carriage adapted to be propelled in a forward direction during an operation on a workpiece; a blowpipe-supporting arm pivotally connected to said carriage and extending in a rearward direction from such pivotal connection, said arm having an end portion freely movable vertically and adapted to bear against successive surface portions of the workpiece as said carriage is propelled in such forward direction; and a blowpipe between said carriage and said pivotal connection and secured to said arm adjacent such freely-movable end portion, whereby said arm maintains the gas jet discharge orifice means of the blowpipe at a substantially constant distance from the surface of the workpiece during such operation.

2. Blowpipe apparatus comprising, in combination, a carriage adapted to be propelled in a forward direction during an operation on a workpiece; a blowpipe-supporting arm pivotally connected to said carriage and extending in a rearward direction from such pivotal connection, said arm having an end portion freely movable vertically and adapted to bear against successive surface portions of the workpiece as said carriage is propelled in such forward direction; and a blowpipe secured to said arm adjacent such freely movable end portion, whereby said arm maintains the gas jet discharge orifice means of the blowpipe at a substantially constant distance from the surface of the workpiece during such operation, in combination with mechanism operable to progressively vary the inclination of said blowpipe from a trailing angle to a leading angle

relative to said surface during free vertical and forward movements of said end portion of the blowpipe-supporting arm.

3. Blowpipe apparatus for thermochemically cutting elongated stock such as solid steel bars of round and rectangular cross section, such apparatus comprising a carriage having an extension adapted to overhang said stock during a cutting operation thereon; propelling means adapted to advance said carriage in a forward direction toward said stock to move said extension transversely of and above said stock; a blowpipe-supporting arm pivotally connected to said extension and extending rearwardly and downwardly from such pivotal connection, said arm having an end portion freely movable vertically and adapted to bear against successive surface portions of the stock as said carriage is propelled in such forward direction toward said stock; and a cutting blowpipe disposed between said carriage and said pivotal connection and secured to said arm adjacent such freely-movable end portion, the construction and arrangement being such that said arm maintains the gas jet discharge orifice means of said blowpipe at a substantially constant distance from the surface of the stock during the cutting operation.

4. Blowpipe apparatus for thermochemically cutting elongated metal stock such as solid steel bars of round and rectangular cross-section, such apparatus comprising a carriage having an extension adapted to overhang said stock during a cutting operation thereon; propelling means adapted to advance said carriage in a forward direction toward said stock to move said extension transversely of and above said stock; a blowpipe-supporting arm pivotally connected to said extension and extending in a rearward direction from such pivotal connection, said arm having an end portion freely movable vertically and adapted to bear against successive surface portions of the stock as said carriage is propelled in such forward direction; a cutting blowpipe secured to said arm adjacent such freely movable end portion and angularly adjustable in the plane of the resulting kerf, the construction and arrangement being such that said arm maintains the gas jet discharge orifice means of said blowpipe at a substantially constant distance from the surface of the stock during the cutting operation, and mechanism for progressively varying the angular position of said blowpipe during free vertical and forward movements of said end portion of the blowpipe-supporting arm, to discharge the oxygen cutting jet rearwardly at the beginning and forwardly at the completion of the cutting operation.

5. Blowpipe apparatus as claimed in claim 3, wherein said carriage is reciprocable, said propelling means also is adapted to retract said carriage in a direction away from the stock and to its initial position upon completion of the cutting operation, and said apparatus includes mechanism for lifting the freely-movable end portion of said arm and the blowpipe secured thereto relative to said carriage extension and about the pivotal connection of said arm thereto, to maintain said end portion and blowpipe both clear of said stock during such retraction of said carriage.

6. Blowpipe apparatus comprising, in combination, a carriage adapted to be propelled as a forward stroke for an operation upon a workpiece; a blowpipe supporting arm pivotally connected to said carriage and extending in a rearward di-

rection from such pivotal connection; and a blowpipe carried by the rearward portion of said arm and located between said carriage and said pivotal connection; said arm having a front cam portion of its under surface adapted to engage and bear against the surface of the workpiece and ride up said surface as said carriage moves forward during the initial portion of its stroke and thereby raise said blowpipe; said under surface having a skid portion at the end of said cam portion adapted to ride onto the surface of said stock as said stock leaves said cam portion and continue in engagement with successive portions of said surface during the major portion of said forward stroke to maintain the nozzle of said blowpipe at a substantially constant distance from the surface of said workpiece.

7. Blowpipe apparatus comprising, in combination, a carriage adapted to be propelled as a forward stroke for an operation on a workpiece; a blowpipe supporting arm pivotally connected to said carriage and extending in a rearward direction from such pivotal connection; and a blowpipe carried by said arm and located between said carriage and said pivotal connection; said arm having a front portion of its under surface curved downwardly to engage and bear against successive portions of the surface of the workpiece and ride up said surface as said carriage moves forward during the initial portion of its stroke and thereby raise said blowpipe; said under surface having a downward projection at the end of said downwardly curved portion adapted to ride onto the surface of said stock as said stock leaves said downwardly curved portion and continue in engagement with successive portions of said surface during the major portion of said forward stroke to maintain the nozzle of said blowpipe at a substantially constant distance from the surface of the workpiece.

8. Blowpipe apparatus comprising, in combination, a carriage adapted to be propelled as a forward stroke for an operation upon a workpiece; a blowpipe supporting arm pivotally connected to said carriage and extending rearwardly therefrom; and a blowpipe carried by the rearward portion of said arm and located between said carriage and such pivotal connection; said arm having a skid portion adapted to bear against successive surface portions of said workpiece as said carriage is propelled in such forward direction to maintain the blowpipe nozzle at a substantially constant distance from the workpiece surface; said arm having a rear cam portion of its under surface curved upwardly and rearwardly to engage successive portions of the workpiece surface and ride down the same during the final portion of said forward stroke to lower the blowpipe nozzle closer to the workpiece.

9. Blowpipe apparatus comprising, in combination, a carriage adapted to be propelled in a forward direction during an operation on a workpiece, a blowpipe supporting arm pivotally connected to the front end of said carriage and extending rearwardly therefrom and having a transverse fork; a blowpipe holder having a transverse yoke pivoted to said fork, and a blowpipe mounted in said holder and extending through said yoke with its nozzle adjacent the pivotal axis of said yoke and fork.

10. Blowpipe apparatus comprising, in combination, a carriage adapted to be propelled in a forward direction during an operation on a workpiece; a blowpipe-supporting arm pivotally connected to the front end of said carriage and ex-

tending rearwardly therefrom and having a transverse fork provided with lugs adapted to engage successive portions of the surface of said workpiece as said carriage moves forward, to maintain said blowpipe nozzle a substantially constant distance from the surface of said workpiece; a blowpipe holder having a transverse yoke pivoted to said fork; and a blowpipe mounted in said holder and extending through said yoke with its nozzle adjacent the pivotal axis of said yoke and fork.

11. In blowpipe apparatus, a blowpipe-supporting arm having a transverse fork, a blowpipe holder having a transverse yoke pivoted to said fork, a blowpipe mounted in said holder and extending through said yoke with its nozzle adjacent the pivotal axis of said yoke and fork and a collar in the fork of said arm and connected to said blowpipe and yoke and provided with preheat gas passages terminating in tips directed toward the surface of said workpiece in advance of the gas jet discharge from said blowpipe nozzle.

12. Blowpipe apparatus comprising in combination a feed beam adapted to be propelled in a forward direction during an operation on elongated metal stock and in a rearward direction for a return stroke; a transversely extending support rigidly mounted on the front end of said feed beam; a blowpipe unit mounted on said support and adjustable thereon longitudinally of said support and transversely of said beam, said unit comprising a frame, a blowpipe supporting arm pivoted to the lower portion of said frame and extending rearwardly therefrom, and a blowpipe holder pivotally carried by the rear portion of said arm.

13. Blowpipe apparatus as claimed in claim 12, in combination with a transverse operating rod connected to said blowpipe holder, and means for moving said operating rod longitudinally of said feed beam to tilt said blowpipe holder about its pivotal connection to said arm.

14. Blowpipe apparatus as claimed in claim 12, in combination with a rock shaft journaled on said support and having a transversely extending cam surface, a crank on said blowpipe supporting arm and having a follower engaging said cam surface, and means movable longitudinally of said feed beam for rocking said cam surface and causing said crank to raise said blowpipe supporting arm and maintain it clear of said stock during said return stroke.

15. In a blowpipe machine for thermochemically operating upon elongated metal stock, said machine having a main boom, and means for supporting said main boom in position extending transversely of said stock, the improvement which comprises a feed beam extending longitudinally of said main boom and slidably carried thereby and means for propelling said feed beam relative to said main boom and longitudinally thereof for movement toward and over said stock, a blowpipe support extending transversely of the front end of said beam, and a blowpipe supporting arm pivoted on said support and extending rearwardly therefrom, and a blowpipe carried by the rear portion of said arm whereby said longitudinal movement of said feed beam relative to said main beam moves said blowpipe transversely of said stock.

16. In a blowpipe machine for thermochemically operating upon elongated metal stock, a base adapted to be mounted at one side of said stock, a main boom, and means carried by said main boom extending over said stock for supporting

a blowpipe and movable relative to said boom for propelling said blowpipe transversely of said stock, the improvement which comprises front and rear links having their lower ends pivoted on said base, said main boom adapted to extend transversely to said stock and having front and rear portions pivoted respectively on the upper ends of said links, whereby said main boom is mounted for substantially parallel movement with respect to said base and transversely of said stock, whereby said means may be moved with said boom on said links from an inoperative position away from said stock to an operative position toward said stock.

17. Blowpipe apparatus for thermochemically cutting elongated metal stock, such apparatus comprising, in combination, a support movable toward and away from said stock; a carriage mounted on said support and movable relatively thereto toward and away from said stock; a blowpipe-supporting arm pivotally connected to said carriage and extending from such pivotal connection in a direction opposite to the direction of movement of said carriage toward said stock, said arm having an end portion freely movable vertically and adapted to bear against successive surface portions of the stock during a cutting operation; a cutting blowpipe secured to said arm adjacent such freely movable end portion; mechanism for moving both said support and said carriage toward and away from said stock and operable to move such freely movable end portion of said arm to bear against said stock and position said blowpipe to start the cutting operation; and means for propelling said carriage relatively to said support and toward said stock to move said arm and said blowpipe across the stock to cut the latter.

18. Blowpipe apparatus for thermochemically cutting elongated metal stock, such apparatus comprising, in combination, a support or boom swingable toward and away from said stock; a carriage mounted on said support and movable relatively thereto toward and away from said stock; a blowpipe-supporting arm pivotally connected to said carriage and extending from such pivotal connection in a direction opposite to the direction of movement of said carriage toward said stock, said arm having an end portion freely movable vertically and adapted to bear against successive surface portions of the stock during a cutting operation; a cutting blowpipe secured to said arm adjacent such freely movable end portion; mechanism for rapidly swinging both said support and said carriage toward and away from said stock to and from a position to start the cut and operable to move such freely movable end portion of said arm to bear against said stock and position said blowpipe to start the cutting operation; and means operable after said rapidly swinging movement for propelling said carriage relatively to said support and toward said stock to move said arm and said blowpipe across the stock to advance the blowpipe for cutting the stock.

19. Blowpipe apparatus for thermochemically cutting elongated metal stock, such apparatus comprising, in combination, a support movable toward and away from said stock; a carriage mounted on said support and movable relatively thereto toward and away from said stock; a blowpipe-supporting arm pivotally connected to said carriage and extending from such pivotal connection in a direction opposite to the direction of movement of said carriage toward said stock,

said arm having an end portion freely movable vertically and adapted to bear against successive surface portions of the stock during a cutting operation; a cutting blowpipe secured to said arm adjacent such freely movable end portion; and mechanism for moving both said support and said carriage toward and away from said stock and including means operable to move such freely movable end portion of said arm into position to bear against said stock and position said blowpipe to start the cutting operation, and means for propelling said carriage relatively to said support and toward said stock to move said arm and said blowpipe across the stock to cut the latter; said mechanism being operable after the completion of the cutting stroke for lifting said end portion and thereby lifting the blowpipe clear of the stock for the return stroke, retracting said carriage to return said arm and blowpipe to starting position, and then retracting both said support and carriage to move said carriage, arm and blowpipe away from the stock.

20. Blowpipe apparatus for thermochemically cutting elongated metal stock of polygonal cross-section, comprising in combination, a carriage adapted to be propelled in a forward direction during an operation on said stock, a blowpipe-supporting arm pivotally connected to said carriage and extending in a rearward direction from such pivotal connection, said arm having an end portion freely movable vertically and provided with a work-engaging undersurface, successive portions of such work-engaging surface being adapted to bear against a corner of said stock as said carriage is propelled in such forward direction, and a blowpipe secured to said arm adjacent such freely movable end portion, whereby said arm maintains the gas jet discharge orifice means of the blowpipe at a substantially constant distance from the surface of said stock during such operation, and mechanism cooperating with said blowpipe for controlling its position relative to said supporting arm for progressively varying the inclination of said blowpipe relatively to the surface of said stock from a lagging angle during operation on said corner to a leading angle during operation on said surface.

21. Blowpipe apparatus for thermochemically cutting elongated metal stock, such apparatus comprising a carriage having an extension adapted to overhang said stock during a cutting operation thereon, propelling means adapted to advance said carriage in a forward direction to move said extension transversely of and above said stock, a blowpipe-supporting arm pivotally connected to said extension and extending in a rearward direction from such pivotal connection, said arm having an end portion freely movable vertically and provided with a work-engaging undersurface successive portions of which are adapted to bear against successive surface portions of the stock as said carriage is propelled in such forward direction, and a cutting blowpipe pivoted to said arm adjacent such freely movable end portion whereby said arm maintains the gas jet discharge orifice means of said blowpipe at a substantially constant distance from the surface of the stock during the cutting operation, and means cooperating with said blowpipe above its pivot to control the angle thereof to start the cut with the blowpipe held at a trailing angle and to complete the cut with the blowpipe held at a leading angle.

22. Blowpipe apparatus for thermochemically cutting stock such as solid steel bars of round

15

and rectangular cross-section, such apparatus comprising a reciprocable carriage having an extension adapted to overhang said stock during a cutting operation, propelling means adapted to advance said carriage in a forward direction to move said extension transversely of and above said stock, a blowpipe supporting arm pivotally connected to said extension and extending in a rearward direction from such pivotal connection, said arm having an end portion freely moving vertically and having a work-engaging undersurface, successive portions of which are adapted to bear against successive surface portions of the stock as such carriage is propelled in such forward direction, and a cutting blowpipe secured to said arm adjacent such freely movable end portion, the construction and arrangement being such that said arm maintains the gas jet discharge orifice means of said blowpipe at a substantially constant distance from the surface of the stock during the cutting operation, said propelling means being also adapted to retract said carriage to its initial position upon the comple-

16

tion of the cutting operation, and said apparatus including means for lifting the freely movable end portion of said arm and the blowpipe secured thereto clear of said stock during such retraction of said carriage.

ARTHUR M. KELLER.
